APPARATUS FOR REAMING WELLS

Ford W. Harris, Los Angeles, Calif.

Application May 27, 1946, Serial No. 672,498

5 Claims. (Cl. 255—73)

1

My invention relates to the art of drilling wells, and, since it has a special utility when used in deep oil wells although it is applicable to other uses, the following description will be principally directed to the use of the invention in oil wells.

My invention relates to the art of drilling wells and is particularly useful in drilling wells by the rotary system in which a string of drill pipe is rotated in the well by means of a rotary table on the derrick floor above the well. The lower end of the string of drill pipe carries a bit which cuts or "makes hole" as it is rotated and rotary mud, a water suspension of clay or other finely divided solid material, is pumped down through the drill pipe and through orifices in the bit near the bottom of the well; the mud then flowing upwardly through the well outside the drill pipe, carrying the small particles of rock, or cuttings of the bit, to the surface, the cuttings being then removed from the mud which is recirculated.

It is an object of my invention to provide a rotary reamer by which the hole made by the bit is enlarged in diameter by cutting away the walls of the well. Rotary reamers are well known in the art.

It is often desirable after casing, used to line the wall of the well, has been set in place and the lower end cemented, to ream or enlarge the diameter of the hole below the casing to a diameter greater than the inside diameter of the casing, this operation being known as "underreaming." It is a further object of my invention to provide a rotary underreamer for this purpose. Rotary underreamers must be, and are now, so made that the cutters thereof may be retracted into such a position that the reamer may pass downwardly through the casing already set in the well, then expanded to a position in which they will cut the wall of the well to a larger diameter than the inside diameter of the casing, and then retracted to their original position so that the underreamer may be readily withdrawn upwardly through the casing. Rotary underreamers that so operate are well known in the art, and underreamers embodying my invention have this old method of operation.

My invention differs from those now known in the art in that the cutters of underreamers embodying my invention: (a) can be moved to an expanded position by starting or increasing the flow of rotary mud through the drill pipe or to a retracted position by stopping or reducing the rate of flow of said mud so that the position of

2

the cutters with relation to the wall of the well is at all times under control of the operator; (b) are each distinct and separate from the other cutters, the force with which each cutter is forced to cut the wall of the well being dependent solely upon rate of flow of the mud and quite independent of the position or condition of any other cutter. Since these cutters are each independently impelled and each propelled outwardly by the full pressure of the mud, the number of cutters can be multiplied, as many as thirty-two cutters being used in a single underreamer.

The results are accomplished by means of new methods of mounting and moving the cutters which may be briefly described as follows: each cutter is carried on the outer end of a piston sliding in a cylindrical opening in the body of the reamer, the inner end of the piston being subjected to mud pressure. The axis of the piston is in a direction passing through the wall of the well so that as the piston moves outwardly or away from the vertical axis of the well the cutters are forced into contact with and cut the wall of the well and thereby ream the hole. I prefer to use cutters of the rotary toothed type which are old in the art but any other well known form of cutter may, of course, be used. I prefer to use stems coaxial with the pistons and rigidly secured thereto which pass through the wall of the reamer body and which are provided with means outside the body for limiting the outward travel of the pistons. These stems add greatly to the strength and rigidity of the pistons and, as far as I know, are new in the art.

My invention further embodies a feature not found, to my knowledge, in the prior art in that I provide means for preventing the piston from turning about its axis in its cylindrical opening.

More narrowly considered, the invention resides in certain constructional details hereinafter described or claimed or to be claimed.

Certain features shown herein are shown and claimed in my application Serial No. 670,932, filed May 20, 1946, the device shown in said application not being an underreamer but a simple reamer used to smooth and straighten the hole.

Referring to the drawings, which are for illustrative purposes only,

Fig. 1 is a view, partly in section, of a reamer embodying my invention;

Fig. 2 is a section on a plane represented by the line 2—2 of Fig. 1, this plane being viewed in the direction of the arrows adjacent the ends of that line;

Fig. 3 is an enlarged view of a cutter assembly;

Fig. 4 is a section on a plane represented by the line 4—4 of Fig. 2, this plane being viewed in the direction of the arrows adjacent the ends of that line;

Fig. 5 is a view of a portion of the reamer, a portion thereof being shown in section on a plane represented by the line 5—5 of Fig. 3, this plane being viewed in the direction of the arrows adjacent the ends of that line. In this view the cutter assembly is in expanded or maximum cutting position; and

Fig. 6 is a view similar to Fig. 4 with the cutter assembly in its retracted or minimum cutting position.

In my invention I may use the novel form of reamer shown in Figs. 1 to 6, inclusive. In the reamer shown in these drawings, I provide a body 10 of cylindrical shape which is provided at its upper end with a frusto-conical cavity 11 which is threaded to receive the pin 12 of a tool joint 13, in which drill pipe 14 is threaded. The body 10 is somewhat smaller than the internal diameter of a casing 15 which may be cemented in the bore 16 of a well. The tool joint 13 has a central hole 17 which connects the interior 18 of the drill pipe 14 with a central passageway 19 extending entirely through the body 10 of the reamer.

Slidably freely within limits in the body 10 are a plurality of cutter assemblies 20 which may all be alike. Each section of the reamer may have eight cutter assemblies, and several sections such as that shown in the drawings may be coupled together to provide a reamer having sixteen or more cutter assemblies 20. Each cutter assembly consists of a piston 21 which is cylindrical about the axis 22—22 of a cylindrical cavity 23 in the body 10. A cutter recess 24 of a shape best shown in Fig. 2 is cut transversely in the outer end of the piston 21, leaving two bearing members 25. A pin 26 passes through the bearing members 25 and carries a cutter 30. The cutter may be provided with teeth 27, as best shown in Fig. 2, or it may have teeth of any other shape now used in similar reamers. In a recess in the wall of the cavity 23 I place outer packing rings 28, now known as "O-rings" and in general use in hydraulic installations. These O-rings allow the piston 21 to slide along the axis 22—22 and prevent fluid from passing between the outer wall of the piston 21 and the inner wall of the cavity 23. Preferably formed integrally with the piston 21 is a cylindrical stop 31 and a tail bolt 32. The tail bolt passes through a hole 33 connecting the cavity 23 with a similar cavity 34 coaxial with the cavity 23, inner O-rings 35 being placed in the wall of the hole 33. The inner O-rings 35 prevent fluid from escaping through the hole 33 around the bolt 32. Threaded on the outer end of the bolt 32 is a nut 36 which is held against rotation on the bolt 32 by a cotter pin 37.

The nut 36 limits the distance the cutter assembly 20 can move out of the body 10, and the stop 31 limits the distance the assembly 20 can move into the body 10, the total movement being indicated by the dimension a shown in Fig. 6.

With the cutter assembly in its retracted position as shown in Fig. 6, only a few of the teeth of the cutter 30 project beyond the body 10, and in the expanded position of the cutter assembly as shown in Figs. 2 and 4, these teeth have moved outwardly through the radial distance a .

Preferably formed integrally with or welded to

the piston 21 are four wings 40 which fit in slots 41 formed in the body 10 and best shown in Fig. 5. These wings 40 are separated by a distance b , which is a little in excess of the diameter of the pin 26, which may be inserted in and withdrawn from the bearings 25 through this space. The wings 40 are cut away at an angle, as shown at 42 in Fig. 4, so that if the reamer is pulled upwardly into the casing 15 the cutter assembly 20 will be forced out of its expanded position, as shown in Fig. 4, into its retracted position, as shown in Fig. 6. Similarly, if the reamer is lowered into a small hole slightly larger than the body 10, the cutter assemblies will be forced into their retracted position. The parts are so proportioned that with the cutter assembly in its extreme expanded position the pin 26 is inside the recess 23, being held from moving farther outwardly by the nut 36. Upon loosening the nut, the piston 21 may be moved far enough out of the body 10 to enable the pin 26 to be withdrawn to replace the cutter 30.

Formed on the bottom of the body 10, as shown in Fig. 1, is a conical threaded pin 50, which is similar to the tool joint pin 12 and upon which a bit may be secured, the bit being fed with circulating drilling mud through the passage 19, the reamer when so used above the bit reaming the hole as fast as the bit cuts it. When used without a bit, that is, when used simply for reaming and straightening a previously drilled hole, a conical end 51 may be secured on the pin 50. This end 51 carries a bushing 52 having a hole 53 considerably smaller than the passage 19. The purpose of the small hole 53 is to cause pressure to build up in the passage 19 due to constriction of flow in the hole 53. Many bits have similar constricted openings which tend to also build up pressure, and, if not, the opening through which mud flows to the bit may be constricted by a bushing (not shown).

The passage 19 is first drilled through the body 10, and as the cavities 23 are formed they intersect the passage 19 so that the space below the piston 21 and between the O-rings 28 and 35 is always in open communication with the passage 19. If, by constricting the flow of fluid below the reamer, pressure is built up in the passage 19 greater than the pressure of the fluid surrounding the body 10, the piston forces each cutter assembly outwardly from the retracted position shown in Fig. 6 toward the expanded position shown in Figs. 2 and 4, this outward movement being limited by contact of the cutter 30 with the wall of the well, or where the well has been reamed to maximum diameter by the nut 36.

The reamer is put in operation by suspending the drill pipe 14 from the derrick and attaching the body 10 to the tool joint pin 12 on the bottom of the drill pipe. The bit, or conical, end 51 is then screwed onto the bottom of the body 10. There being no fluid flowing through the passage 19, each of the cutter assemblies 20 can be readily pushed into retracted position, as shown in Fig. 6, and the reamer can be readily lowered through the casing 15 until the reamer is below the lower end of this casing. The drill pipe is then rotated and the mud pump is started and mud flows downwardly through the drill pipe 14 and through the central passage 19 in the body 10. This flow being restricted below the reamer, pressure builds up in the passage 19, and this pressure is transmitted equally and uniformly to all of the pistons 21, forcing them all outwardly with equal force

until the cutters 30 bear on the inner wall of the well and roll thereon, cutting this wall by the action of the teeth on the cutters 30, in a manner well known in the drilling art in which such toothed drilling cutters have long been used in drilling bits. The reamer is slowly lowered in the well, and each cutter progressively from top to bottom acts to cut or break off material from the walls until the maximum diameter of well bore is produced, when the upper cutters are rendered inoperative, further outward travel being stopped by the nuts 36. When the reamer is removed from the well, the teeth of the lower cutters 21 will be found to be blunted or worn. If the upper cutters are found to be without such wear, this is an indication that the hole has been reamed to maximum diameter. If all the cutters are found to be equally worn, it is equally obvious that a full hole has not been cut, but with a two-section reamer, or with sixteen cutters above the bit, the reamer will usually ream more hole than any of the present bits will make, and there will ordinarily be very little wear on the cutters of the upper reamer section.

When it is desired to remove the reamer from the hole, rotation and circulation of fluid is stopped, and there is now no pressure forcing the cutter assemblies 20 outwardly. As the reamer enters the casing 15, each cutter assembly 20 is forced back into the body by the inclined surfaces 42 of the wings 40, striking the casing 15 or the wall of the well just below the casing, and the reamer moves freely in its upward trip through the casing.

As soon as the reamer emerges from the well, the cutters 21 are inspected for wear, and any cutters showing undue wear are replaced with the reamer hanging in place. The replacement of a cutter involves removing the cotter pin 37 and backing the nut off to allow the cutter head to be moved out far enough to allow the pin 26 to be removed, thus releasing the worn cutter 21. A sharp cutter is then put in place and a new pin is supplied. The nut 36 is then screwed home, the cotter pin 37 is replaced, and the reamer is ready for another trip into the hole. The cutters 20 and pins 36 will show considerable wear and must be frequently replaced, but none of the other parts except the bushing 53, which tends to be cut by high velocity mud, will wear materially over long periods of use.

Every drill bit with which I am familiar tends to wear away on its outer edges with us and thus tends to progressively produce a bore of smaller diameter. A hole that starts with a new bit at six inches in diameter soon shrinks to five and one-half inches as the bit wears away, the bit otherwise continuing to make hole at a satisfactory rate. If enough sections of my reamer are used to have a few of the upper cutters performing no duty, regardless of the inevitable wear of the bit, the hole above the reamer will be of uniform diameter, and this diameter will be ten to fifteen per cent greater than the maximum diameter cut by the bit. This results in a smooth hole of uniform and greater diameter than the inside of the casing 15.

One great advantage of my reamer is that it can be used to ream upwardly. In other words, it can be dropped to the bottom of a small hole and, when rotated during its travel in an upward direction, will ream hole to maximum diameter back to the casing 15.

I claim as my invention:

1. In an underreamer for use in wells of the

type in which a body attached to a drilling string composed of sections of drill pipe is rotated by said string and carries a cutter or cutters which may be expanded and pushed outwardly to contact and cut the wall of the well or retracted and pulled inwardly to a position which allows the underreamer to be withdrawn through casing of smaller diameter than the hole produced below the casing by the reamer, the combination of: 10 such a body having a circulation channel through which a liquid such as rotary mud may be forced downwardly from the drill pipe, said liquid flowing upwardly at a reduced pressure through the space between the body and the wall of the well, 15 said body having a cylindrical bore therein which is in open communication with said circulation channel, the axis of said bore passing through the wall of the well when said body is in working position therein; a piston which is free to move along the axis of said bore, said piston being so placed in said bore that it tends to prevent said liquid from escaping from said channel and through said bore into the well; a cutter spindle carried by the outer end of said piston; and a 20 toothed cutter free to revolve on said spindle, said spindle being so placed with relation to said piston that the teeth of said cutter are forced into cutting relation to the wall of the well when said piston moves along said axis toward said wall.

2. In an underreamer for use in wells of the type in which a body attached to a drilling string composed of sections of drill pipe is rotated by said string and carries a cutter or cutters which may be expanded and pushed outwardly to contact and cut the wall of the well or retracted and pulled inwardly to a position which allows the underreamer to be withdrawn through casing of smaller diameter than the hole produced below the casing by the reamer, the combination of: 30 such a body having a circulation channel through which a liquid such as rotary mud may be forced downwardly from the drill pipe, said liquid flowing upwardly at a reduced pressure through the space between the body and the wall of the well, 35 said body having a cylindrical bore therein which is in open communication with said circulation channel, the axis of said bore passing through the wall of the well when said body is in working position therein; a piston which is free to move 40 along the axis of said bore, said piston being so placed in said bore that it tends to prevent said liquid from escaping from said channel and through said bore into the well; a stem attached to said piston and concentric with the axis of said piston, said stem extending in fluid-tight relationship through an opening in the wall of said body, said opening being concentric with the axis of said bore and extending through the wall of the body in a direction axially opposite to said bore; fastening means on the outer end of said stem of larger diameter than said stem and said stem opening; and a cutter carried by said piston and so placed that said cutter is forced against and cuts the wall of the well when said piston moves along said axis toward said wall.

3. In an underreamer for use in wells of the type in which a body attached to a drilling string composed of sections of drill pipe is rotated by said string and carries a cutter or cutters which 50 may be expanded and pushed outwardly to contact and cut the wall of the well or retracted and pulled inwardly to a position which allows the underreamer to be withdrawn through casing of smaller diameter than the hole produced below the casing by the reamer, the combination of:

such a body having a circulation channel through which a liquid such as rotary mud may be forced downwardly from the drill pipe, said liquid flowing upwardly at a reduced pressure through the space between the body and the wall of the well; said body having a cylindrical bore therein which is in open communication with said circulation channel, the axis of said bore passing through the wall of the well when said body is in working position therein; a piston which is free to move along the axis of said bore, said piston being so placed in said bore that it tends to prevent said liquid from escaping from said channel and through said bore into the well; a stem attached to said piston and concentric with the axis of said piston, said stem extending in fluid-tight relationship through an opening in the wall of said body, said opening being concentric with the axis of said bore and extending through the wall of the body in a direction axially opposite to said bore; fastening means on the outer end of said stem of larger diameter than said stem and said stem opening; a cutter spindle carried by the outer end of said piston; and a toothed cutter free to revolve on said spindle, said spindle being so placed with relation to said piston that the teeth of said cutter are forced into cutting relation to the wall of the well when said piston moves along said axis toward said wall.

4. In an underreamer for use in wells of the type in which a body attached to a drilling string composed of sections of drill pipe is rotated by said string and carries a cutter or cutters which may be expanded and pushed outwardly to contact and cut the wall of the well or retracted and pulled inwardly to a position which allows the underreamer to be withdrawn through casing of smaller diameter than the hole produced below the casing by the reamer, the combination of: such a body having a circulation channel through which a liquid such as rotary mud may be forced downwardly from the drill pipe, said liquid flowing upwardly at a reduced pressure through the space between the body and the wall of the well, said body having a cylindrical bore therein which is in open communication with said circulation channel, the axis of said bore passing through the wall of the well when said body is in working position therein; a piston which is free to move along the axis of said bore, said piston being so placed in said bore that it tends to prevent said liquid from escaping from said channel and through said bore into the well, a member so placed as to prevent said piston from turning about the axis of said piston in said bore but which allows the piston to slide freely therein; a stem attached to said piston and concentric with the axis of said piston, said stem extending in fluid-tight relationship through an opening in the wall of said body, said opening being concentric with the axis of said bore and extending through the wall of the body in a direction axially opposite to said bore; fastening means on the outer end of said stem of larger diameter than said stem and said stem opening; and a cutter carried by said piston and so placed that said

5 cutter is forced against and cuts the wall of the well when said piston moves along said axis toward said wall.

5. In an underreamer for use in wells of the type in which a body attached to a drilling string composed of sections of drill pipe is rotated by said string and carries a cutter or cutters which may be expanded and pushed outwardly to contact and cut the wall of the well or retracted and pulled inwardly to a position which allows the underreamer to be withdrawn through casing of smaller diameter than the hole produced below the casing by the reamer, the combination of: such a body having a circulation channel through which a liquid such as rotary mud may be forced downwardly from the drill pipe, said liquid flowing upwardly at a reduced pressure through the space between the body and the wall of the well; said body having a cylindrical bore therein which is in open communication with said circulation channel, the axis of said bore passing through the wall of the well when said body is in working position therein; a piston which is free to move along the axis of said bore, said piston being so placed in said bore that it tends to prevent said liquid from escaping from said channel and through said bore into the well; a member so placed as to prevent said piston from turning about the axis of said piston in said bore but which allows the piston to slide freely therein; a stem attached to said piston and concentric with the axis of said piston, said stem extending in fluid-tight relationship through an opening in the wall of said body, said opening being concentric with the axis of said bore and extending through the wall of the body in a direction axially opposite to said bore; fastening means on the outer end of said stem of larger diameter than said stem and said stem opening; a cutter spindle carried by the outer end of said piston; and a toothed cutter free to revolve on said spindle, said spindle being so placed with relation to said piston that the teeth of said cutter are forced into cutting relation to the wall of the well when said piston moves along said axis toward said wall.
